Application October 29, 1930, Serial No. 492,020
In Austria July 3, 1930

13 Claims. (Cl. 250—27.5)

This invention relates to indirectly heated glowing or hot cathodes for discharge tubes. The indirect heating of discharge tubes permits of the employment of electric currents of any kind and property, and therefore also of the employment of any sources of current, irrespective of the operation of the tubes. It has already been proposed to make tubes of the described order for operation with the voltages actually at the disposal of the user, such as the normal line voltages. The proposals made in this direction have not been put into practice for the reason that the results achieved thereby, considered from the points of view of economy, length of life, and time required for starting, do not attain the standards expected of the systems of indirect cathode heating at present generally in use, in which systems the low voltage heating current is either derived from special current sources, or is produced by transformation of the line current. The present invention has for its object to provide a method of indirect cathode heating with line current which shall be free of the above-mentioned drawbacks. To this end a heating wire consisting in the main of metal and having this great length which is necessary for consuming the high voltage with a wire of such material is so arranged within a body of insulating material, in utilizing the cross-section of this body, which in its turn is surrounded by the cathode, that the heat output amounts to at least 1-1½ per sq. cm. of effective cathode surface.

No alteration in the usual structure of the discharge tubes is necessitated by the introduction of this new system. It is however necessary to take special measures to accommodate the long length of heating wire used within the space available inside the cathode. This object is achieved by spiraling the wire in a manner known per se, and by concentrating the coil thus obtained within the insulating body situated inside the cathode by laying the same in folds in meander or serpentine formation.

With this arrangement the heating wire need only be heated to a low temperature, a fact which is of great importance for the length of life of the tubes. At the same time only comparatively slight differences of voltage occur between the individual sections of the heating wire, so that, for the prevention of short-circuiting between these sections, it is sufficient to make the insulating layers between these sections as thin as is practically possible. This fact results in the further advantage that the heat capacity of the cathode body is very slight, and, with the employ-

ment of the usual small amount of energy, the cathode attains its working temperature after a comparatively short starting interval. At the same time it becomes further possible to arrange the heating wire in such a concentrated formation that the high voltage applied thereto produces no disturbing effects either of a capacitive or of an inductive order.

This arrangement proves not only particularly effective in regard to the accommodation of the considerable length of wire, required, but also permits, of an economical distribution and concentration of the heat generated, and thus produces very favourably heating conditions. If this circumstance be fully utilized the temperature of the heating wire can be kept down to a minimum which is very little higher than the temperature required for the glowing cathode itself, the dimensions of the wire being so determined within the limits set on the one hand by the voltage employed and on the other hand by the permissible heating limit for the wire under prolonged working that the heating is effected at precisely the temperature which suffices, in the case of the particular method employed for distributing or disposing the wire, to maintain the cathode at the desired temperature. The useful life of the wire is thereby considerably increased.

In some cases it has proved advantageous in accordance with the present invention to make the hot cathode of a discharge tube of several independent parts which are connected in parallel, while the sections of the coiled heating wires which pass through these parts are connected in series. It is possible in this manner to obtain favourable conditions of emission and heating even with heating currents of very high voltage. It is further well known that in the manufacture of hot cathodes the heating of the cathode to a very high temperature is necessary in the course of the so-called baking and ageing processes. If the heating wire according to the present invention were heated to temperatures of this order its life would be considerably shortened thereby, and one of the valuable achievements of the present invention, namely the increase in the length of life of the heating wire, would be sacrificed. In order to avoid this loss the invention provides for the incorporation in the cathode, apart from the coiled heating wire, of an ordinary simple heating wire which can be provided with separately current conducting leading in wires, and is so dimensioned that with the usual low voltage the required high temperature of the emitting layer (about 1200°—1400° C.) during the process of

manufacture can be attained. After the completion of the lamp this latter wire becomes superfluous; it is therefore permissible to overheat the same considerably, since it is only required to 5 function for a short length of time. This wire can, however, be so dimensioned that it can serve for the auxiliary or alternative heating of the tube under normal working conditions with low voltages, so that it thus becomes possible, for 10 example, to have a tube which can be heated both by current from the main and also by current from accumulators.

The heating required during the process of manufacture (for the baking of the tube or for 15 the ageing at the cathode) can also be carried out in another manner which does not entail putting a strain upon the heating wire. In place of a metal tube with a coating of an emitting medium the cathode proper can also consist of a similarly 20 coated wire which is wound into a spiral and through which current can be directly passed for the purpose of the initial heating at high temperature. The normal heating for the operation of the tube after completion is however effected 25 indirectly by means of a heating unit in accordance with the present invention accommodated within the said spiral. In this case also the separate conducting-leads can be so arranged that the tube may be operated alternatively with two 30 different voltages, that is to say with direct or indirect heating.

The main advantages of the invention are first the simplification of the various kinds of apparatus in which tubes of this kind are employed, 35 and secondly the rendering of direct and alternating current of high voltage to be in the same manner applicable to the operation of these tubes. Whereas hitherto direct current sources or lines with a high voltage were precluded from use for 40 the operation of tubes with indirect heating the application of the present invention enables both kinds of current to be employed with equal efficiency also at high voltages in regard both to efficiency and to all other conditions of working.

45 Hot cathodes of the type provided by the invention can be employed wherever indirectly heated cathodes are used, but more especially in luminous and similar discharge tubes.

Several examples of the embodiment of the 50 invention are shown in the accompanying drawing, in which:—

Figs. 1 and 2 illustrate a glowing cathode in which a cylindrical tube coated with an emitting medium is heated by means of a spirally wound 55 medium and repeatedly folded wire each of the folds of which is enclosed in a separate insulating tube.

Figs. 3 and 4 illustrate a modified form of the 60 invention in which the individual folds of the heating wire traverse channels in a ceramic insulating body which fills out the interior of the cathode. These figures also illustrate a manner 65 in which an auxiliary wire can be inserted in addition to the heating wire.

Figs. 5 and 6 show a further modification of the 65 cathode in which the emitting film is carried by a box-shaped carrier having two substantially predominating plane surfaces. In this case again the folds of the heating wire are laid in channels in a ceramic insulating body which fills 70 out the interior of the box-shaped cathode.

Fig. 7 shows yet another modification of the 75 cathode with an insulating body similar to that shown in Figs. 3 and 4, in which, however, the cathode proper consists of a spirally wound wire which is coated with an emitting medium.

Fig. 8 shows a still further modification.

Referring to Figs. 1 and 2 the indirectly heated cathode shown consists of a hollow cylindrical nickel tube *a* which carries a coating of an emitting medium which is heated by means of a heating wire *b* situated in the interior of this tube. This heating wire, as above explained, is of such a length that its resistance suffices, at comparatively high voltages, to generate the required output of heat with the desired not too high temperature. For the purpose of accommodating this length of wire within the space enclosed by the surface to be heated this wire is spirally wound for the whole of its length and in the illustrated example moreover laid in four folds travelling 10 back and forth within the cathode tube. Each fold of the wire is enclosed in a separate insulating tube *c*, and all four tubes are so disposed that they as nearly as possible uniformly fill out the hollow space within the tubular cathode. 15

The heating wire may itself be provided with a coating of insulating material in the manner of enamelled wire. For example, the coils can be provided with a coating of ceramic material by spraying it on the wire with a suitable binder to 20 the required thickness and finally baking it, by which means the wire acquires a suitable coating which is so constituted, in the case of the multiple coils here employed, that it prevents at the same time the deformation of the coil. The coating 25 may also consist of pure glazed aluminium oxide, zirconia, or similar material which is applied in the same manner.

The modified form of cathode shown in Figs. 3 and 4 is distinguished from that described above 30 in that the function of the separate insulating tubes is assumed by a single ceramic insulating body which completely fills out the interior of the tubular cathode. This insulating body is provided with a number of channels (there being 40 four such channels in the example shown in Figs. 3 and 4) which are traversed by the folds of the spirally wound heating wire.

That a sufficient length of heating filament of the appropriate thickness can be accommodated 45 within the cathode is shown by the following specific example:—

The hot cathode is intended for direct connection to a lighting main carrying current of 110 50 volts. The cathode is to consist of a nickel tube of approximately 3 mm. internal diameter and approximately 30 mm. in length (which corresponds to the usual dimensions). In this case a heating coil is employed consisting of tungsten wire of 0.02 mm. diameter. The total length of 55 this wire required to effect the heating in accordance with the present invention is 170 cm. This length of wire can easily be converted by winding into a spiral which, according to the diameter of the turns, measures 80–140 mm. from end to end. 60 This length of spirally wound wire can easily be accommodated within the space enclosed by the cathode if the coil be folded at the most four times.

When current of 220 volts is to be used precisely the same coiled heating filament can be employed, two tubular cathodes being arranged in juxtaposition and connected in parallel, while the heating wires contained therein are connected in series. 65

This latter arrangement has the advantage from the manufacturing point of view that for all usual line voltages the same elements and apparatus can be employed. If it is not desired to make use of this advantage it is possible by slight- 70 75

ly increasing the diameter of the tubular cathode to provide the extra space necessary for all the required additional folds of the spiral (in the example cited).

5 It is thus possible, while retaining the normal dimensions for wire and cathode, to employ all the usual line voltages without difficulty for the purpose of heating.

The length of the heating filament, as already mentioned, can be so determined that its working temperature is kept down to a minimum, with a view to increasing as far as possible its length of life. In this case the total length of wire used is in excess of that strictly required by the voltage 15 or by the highest permissible temperature for the wire under continuous working. In consequence of the uniform distribution of the heating wire in regard to the surface of the cathode, and in consequence of the concentration of the heating effect here obtainable, and also in consequence of the favorable conditions for the transference of heat, it becomes possible through the present invention to maintain a minimum temperature of the heating wire which just suffices to bring the 20 emitting layer up to the required temperature of 700-1000° C., that is to say the wire itself does not require to be heated much beyond this temperature. Through the application of the present invention it also becomes possible, in conjunction 25 with very thin wires, to develop a calorific output which amounts to at least 1-1½ watts per cm² of cathode surface and is generally considerably higher. It is, however, only above this limit that the most favourable, i. e. lowest, temperature of the heating filament under working 30 conditions can be obtained.

A further step in the direction of improving the economy and length of life of the tubes by reducing as far as possible the temperature of the 35 heating wire consists in providing that no more of the energy supplied to the heating wire is allowed to go to waste on the way to the emitting layer than is absolutely unavoidable in consideration of the required insulation between the heating wire and the hot cathode. The procedure is to arrange the heating wire and the metal of the cathode in as close proximity as possible while allowing for the necessary insulation, to which end the metal of the cathode is applied directly to the layer of insulating material surrounding the heating wire, and in addition this layer of insulating material between the heating wire and the metal of the cathode is kept as thin as possible.

55 The proposal has already been made, in connection with cathodes intended for indirect heating with currents of low voltage, to apply the cathode metal directly to the insulating body surrounding the heating element, but clearly not for the purpose of enabling the temperature of the heating wire to be reduced, since this temperature is practically of no consequence for the length of life of the thick wires employed in connection with low voltage heating. Within the 60 scope of the present invention, on the other hand, in view of the fact that even slight reductions in the temperature of the heating wire can be of great importance, this measure is resorted to 65 for the purpose of increasing very considerably the length of life of the tubes. The end in view is not fully achieved by means of this measure alone, but only through at the same time keeping down the insulating layer between several sections of the heating wire and between the heat-

ing wire and the metal of the cathode to the least permissible thickness.

According to this principle, for instance, the channels in the insulating body c in the form of construction shown in Figs. 3 and 4 are to be 5 so disposed so that as little as possible of the heat generated by the heating wires is wasted in heating up the insulating body. The cathode metal is then not, as previously described, fitted over the insulating body in the form of a separately 10 made tube (which would imply the presence of an insulating clearance between the insulating body and the cathode metal), but is directly applied by means of any one of the known processes for this purpose. These processes include 15 e. g. the spraying of the metal with a pistol-atomizer, vapourization, electrolytic depositing, the method of cathode-atomization, etc. In this manner a carrier layer for the emitting medium is obtained which is intimately connected to and 20 therefore adherent to the insulating layer or body, and which can be kept considerably thinner than the above-mentioned cathode tube, and for this reason, if for no other, requires a smaller 25 amount of heating energy. If desired the thickness of the cathode metal layer can be reduced to the lowest limit at which this layer forms a coherent surface throughout.

A form of construction which is particularly 30 advantageous for the attainment of a very low temperature of the heating wire is shown in Fig. 8, in cross-section, on a very much enlarged scale. In this case an independent ceramic insulating body is not employed, but the heating wire b 35 is itself provided, in the manner already described, with an insulating coating c' which in its turn carries a coating a' of the cathode metal. To this carrier layer a' the emitting layer, which is not shown in the drawing, is applied.

40 It will be clear that with a cathode heating element of this type the energy employed for the heating of the emitting layer is conducted to the layer practically without loss, so that the temperature of the heating wire does not require 45 to be appreciably different from that of the emitting layer. By means of this favourable arrangement the duration of the necessary heating-up period is also considerably reduced.

The form of cathode shown in Figs. 5 and 6 50 comprises a box-shaped body which is particularly suitable for use in connection with box-shaped containers and tube structures. In this case a correspondingly shaped insulating body is provided inside the flat rectangular cathode 55 casing, which body permits of the provision of a large number (in the present instance eight) channels hollowed out of the material of the said body. The coiled heating wire is then laid along a meandering course traversing these channels alternately in opposite directions. A glowing cathode of this type is mainly intended for use in connection with particularly high voltages.

65 The high temperature of the glowing cathode required during the process of manufacture for the purpose of baking and ageing the cathode, which temperature varies between 1200° and 1400° C., is preferably not generated by the heating 70 wire itself, in view of the detrimental effect of this step upon the life of the wire which is otherwise very considerably lengthened by the present invention. According to the present invention it is preferable to generate the heat required 75

for this purpose by means of a separate auxiliary heating wire *f* which is passed through the tubular cathode *a* in addition to the heating wire proper (Figs. 3 and 4). This auxiliary wire may 5 be of comparatively large diameter, and can be submitted to a very great strain since it is not called upon to function during the subsequent operation of the tube, and can therefore be short-lived. A wire of this kind can, in consequence 10 of its dimensions, be brought by means of the usual low voltage of 5-20 volts to the temperature required for the rapid and convenient liberation of gas from the cathode. Moreover the ageing of tubes of this type can easily be carried 15 out by means of the auxiliary wire in consequence of the rapid attainment of very high temperatures which is facilitated by the use of this wire.

The auxiliary wire can either be provided with 20 separate leads-out or can be connected to the same leading out points as the heating wire proper. In the latter case the auxiliary wire is rendered inoperative in any suitable manner after 25 the conclusion of the ageing process.

In Figs. 3 and 4 the insertion of an auxiliary wire *f* of this type within a cathode which is filled out with an insulating body is illustrated. The insulating body is provided for this purpose with an 30 additional central channel *g* through which this auxiliary wire is passed. If desired, this auxiliary wire *f* can be connected to separate leading in wires and remain permanently incorporated in the tube, so that it becomes possible to operate 35 a discharge tube of this type with two different voltages, say a line voltage and a low voltage, at will.

In Fig. 7 a further form of the invention is shown in which the cathode consists of a core wire 40 *h* to which the emitting layer is applied and which is wound to form a coil in which the consecutive turns are arranged near to each other. Within this coil there is provided as before an insulating body with channels for the accommodation of 45 the folds of the heating wire. A separate auxiliary heating wire is not provided in this case, since the wire of the coil forming the cathode proper is employed for the purpose of the initial heating, and is to this end taken to suitable leads. 50 During the baking and ageing of the tube the oxide cathode is thus directly heated to the temperature required for this process. The subsequent heating during the operation of the tube is then indirectly effected by means of a coiled heating wire as already described. It is also possible 55 to determine the dimensions of the wires in such a manner that the tube can be heated at will either from the main or from accumulators or any other source of low voltage current, that is to say that 60 the tube can be used either as a directly heated or as an indirectly heated tube, according to the voltage of the current available.

What we claim, is:

1. An indirectly heated cathode for electric discharge tubes, comprising in combination a cathode surface consisting of an auxiliary heater adapted to be heated while aging the cathode, a coating of an emitting medium applied to a part of said cathode surface, a heater within said surface adapted to be connected directly with ordinary electric supply means and consisting of a plurality of helically wound metal filaments having a diameter substantially less than 0.1 mm., said filaments being interconnected in series and being closely adjacent to each other, and heat-

transmitting insulation interposed between said cathode surface and said heater and between adjacent filaments.

2. An indirectly heated cathode for electric discharge tubes, comprising in combination, a cathode surface, a heater within said surface adapted to be connected directly with ordinary electric supply mains and consisting of a plurality of helically wound metal filaments having a diameter substantially less than 0.1 mm., said filaments being interconnected in series and being closely adjacent to each other, and a separate heat-transmitting insulation tube surrounding each one of said filaments.

3. In an indirectly heated cathode for discharge tubes, an insulating body, an electron emitting surface carried by said insulating body and surrounding the same, a plurality of elongated helically coiled conductors connected in series with each other and situated in the insulating body, said conductors consisting of a large number of closely adjacent turns and being situated in close juxtaposition to said electron emitting element to heat the same, and a separate auxiliary wire situated in said insulating body.

4. In an indirectly heated cathode for discharge devices, a heater of a diameter substantially less than 0.1 mm. having an effective resistance to develop a calorific output amounting to at least 1-1/2 watts per cm^2 of cathode surface at the operating voltage, an electron-emitting cathode surface and a carrier therefor surrounding said heater, and a small mass of insulation for said heater serving at least in part to separate it from the cathode carrier and placed in contact with the latter, the mass of said insulation being so small that during the operation of the device the temperature of the heater may be kept substantially the same as that required for the cathode surface quickly to emit electrons when the heater is first connected with a high voltage source.

5. An indirectly heated cathode according to claim 4 and in which the heater is in the form of a plurality of helically coiled conductors connected in series and located within said mass of insulation.

6. An indirectly heated cathode according to claim 4 and in which the space enclosed by the cathode is substantially filled with the insulation with channels formed therein, and the heater in the form of a wire is in a plurality of layers each held within a channel.

7. An indirectly heated cathode according to claim 4 and in which an auxiliary heater is provided within the cathode.

8. In an indirectly heated cathode for discharge devices, a heater having an effective resistance to develop a calorific output amounting to more than 1-1/2 watts per cm^2 of cathode surface at the operating voltage, an electron-emitting cathode surface and a thin carrier therefor surrounding said heater, and a thin layer of insulation separating said heater from the carrier and placed in contact with the latter, the thickness of the insulation and of the carrier being such that during operation sufficient heat is transmitted to the cathode surface when the heater is operated only slightly above the critical temperature of the cathode surface to start the device without undue delay.

9. In an indirectly heated cathode for discharge devices, an electron emitting element, heating means therein adapted to be directly connected to a 110 volt line, and solid insulating

- means separating the heating means from the emitting element, said emitting element encasing and contacting with said insulating means and having a surface area of substantially 3 cm².
- 5 10. An indirectly heated cathode comprising an electron-emitting element for use singly and in series with one another in a plurality of electronic tubes, heating means within said cathode, and solid insulating means separating the heating means from the emitting element, said emitting element encasing and contacting with said insulating means and having a surface area of substantially 3 cm², each of said emitting elements encasing and contacting with its respective 10 insulating means and having a surface area of substantially 3 cm², the heating means of said tubes being connected in series directly to a 110 volt line.
- 10 11. In an indirectly heated cathode for discharge devices, an electron-emitting element and a heater surrounded by said electron-emitting element and consisting of a helically coiled filament of dimensions suitable for a heating voltage of at least 110 volts, the filament being located within coherent insulating material, said electron-emitting element surrounding and in contact with said material and having a superficial area of substantially 3 cm².
- 15 12. In an indirectly heated cathode for discharge devices, an electron-emitting element and a heater surrounded by said electron-emitting element and consisting of a helically coiled filament of a diameter of substantially 0.02 mm. and of a length of substantially 1700 mm. which helically coiled filament is in the form of a plurality of series connected sections within solid insulating material, said electron-emitting element enclosing and contacting with said insulating material and having a surface of substantially 3 cm².
- 15 13. In an indirectly heated cathode for discharge devices, an electron-emitting element, a 15 helically coiled heating wire of a diameter of 0.02 mm. and of a length of 1700 mm., said wire being arranged in a plurality of series connected sections extending through longitudinal perforations in a coherent insulating body, said electron-emitting element enclosing and contacting with said body and having a surface of less than 3 cm².
